D. TREADWELL.
HATCHELING FLAX AND HEMP.

Patented Aug. 18, 1834.

Daniel Headwell.

8366X

Letters Patent (Patented August 18. 1834.)

The Schedule referred to in these Letters Patent and making part of the same, containing a description in the words of the said Daniel Headwell himself, of his improvement in the Machine for Combing or Hatchelling Hemp, Flax and Wool.

Know all men by these Presents, that I, Daniel Headwell, of Boston, in the Commonwealth of Massachusetts, Engineer, have invented an improved machine for dressing, combing, or hatchelling hemp, flax, wool, and other fibrous substances.

To make the construction and mode of using this machine understood, I have herewith annexed complete drawings of the same, which drawings are declared to make a part of this specification. Fig. 1, represents an elevation of the machine; Fig. 2, a plan. A A A, is a wooden frame, bearing the great cylinder B B, which is covered with steel points, or teeth, as shown at C C. The cylinder is completely surrounded by rows of these teeth, although only a portion of them are shown in the drawings. Their form and distance will be understood from those seen at the top of Fig. 1. The cylinder B B rests its shaft in proper boxes on the frame A A, and is furnished with the pulleys D D, E E, F F, G G. D D is a loose pulley capable of turning freely on the axis. E E, F F, G G, are fixed to the axis of B B. On the same frame A A, is placed the small cylinder H H. This cylinder is covered with rows of teeth, a part of which only are shown in the drawings, as at T T. I may remark, moreover, that the teeth are shown in the drawing with square ends, but they are made and should have been represented with sharp points. The cog wheel K K, is fixed upon the shaft of the cylinder H H, and is driven by the pinion L L, fixed upon a shaft, which has, likewise, fixed upon it the pulley M M. Two pieces of plank O O, each of which is formed to a semi-circle, are fixed to the frame A A, at each end of the cylinder H H. The circular edges of these planks are in such position, that a line drawn from end to the other, parallel with the axis of the cylinder, will touch the points of the teeth with which the cylinder is covered. Several bags or sleeves P P P P, are placed over the cylinder H H, being fixed by their ends, to the planks O O. The planks O O are

shown at Fig. 2, but not at Fig. 1, and the lags P.P. are shown at Fig. 1, and not at Fig. 2. R R & C represent rods or cleavers, which are placed, one between every row of teeth with which the cylinder is surrounded. These cleavers are kept from falling out of their places, by two belts of leather S S, which surround them, and are secured to them by thongs. The ends of the cleavers R R, project beyond the ends of cylinder H H. They are, fixed to the inside of each of the planks O O, a wedge or inclined plane, T T. The shape or outline of the sides of these wedges, may be seen in the dotted line at Fig. 1, and their connection with the other parts, is seen at Fig. 2. It will thus be seen that the cleavers R R, as they pass over these wedges, are forced away from the cylinder H H, towards the cylinder B B, so as to approach very near to the teeth of that cylinder. A shaft U, is placed across the frame A A, where it rests in proper boxes. This shaft is commanded by an arrow, to which a weight may be attached, and handle, as seen in the drawings, and has, moreover, fixed to it, the rach V V, seen separately, and in another view, at Fig. 3. The bars of which the rach is formed, lay into the spaces between the teeth on the large cylinder. An open belt must be passed round the pulley E and the pulley H, or if the cylinder H, should be required to move with greater speed, then the belt should pass round the pulleys E and A. The machine is driven by a belt passing from any proper drum, and round the pulley E E. To put the machine in operation, it is only necessary to pass the hemp, flax, wool, or other substance to be operated upon to the cylinder H, by means of a feeding cloth or table, properly arranged for the purpose. The large cylinder being put in motion in the direction of the arrow, the small cylinder, from its connection with it, by the belt pulleys and gears heretofore described, passes with the hemp or wool upon it, under the lags or stakes P P P P. These stakes press the hemp or wool into the teeth H. Then the forward ends of the material thus carried in the teeth are at the point nearest to the large cylinder, the cleavers R R, rising on the wedges T T, cause those ends out of the teeth H, and they are struck by the teeth C C, by which the operation of clearing, combing or scutching, is performed. The cylinders continuing to move in this way, when the hindermost ends of the fibres of hemp or wool, arrive at the place of the wedge T T, the fibres slip from the teeth of the cylinder H, into those of B, and are carried round with them, being passed down upon the cylinder by the

action of the rack V V. The supply of hemp or wool is to be continued to the cylinder H H, until the teeth of the cylinder B B are sufficiently filled, when the main belt must be guided to the pulley D D, which permits the motion of the machine to cease. The rack V V, is prone to be thrown back, and the hemp, or wool, being pulled out of the teeth of B B, at any point on its circumference, is taken off in a flax, when it may be drawn into a roving, or disposed of in any way that may be required. The drawings hereto annexed, were made from a machine for working hemp. In a machine for wool, or flax, it will be necessary to reduce the size, to conform to the staple used.

I do not claim a Patent for each part of the above described machine, in its uncombined state, but for the combination of the two cylinders, and the parts essential to their operation, as herein described.

In witness that the above is a true specification of my said invention, I have hereunto set hand this sixtth day of August, eighteen hundred and thirty four at Boston aforesaid.

Witnessed

C. A. Dame
